(57) **CLAIM**

The ornamental design for a table base, as shown and described.

DESCRIPTION

This application contains subject matter which is related to the subject matter of commonly assigned and co-filed U.S. Design patent application Ser. No. 29/236,496, entitled “Table Base,” by Carl A. Muller, and U.S. Design patent application Ser. No. 29/236,498, entitled “Table Base,” by Carl A. Muller, the entirety of these applications being incorporated herein by reference.

FIG. 1 is a perspective view of a table base in accordance with the new design;

FIG. 2 is a front elevational view thereof, a rear elevational view being a mirror image thereof;

FIG. 3 is a right side elevational view thereof, a left side elevational view being a mirror image thereof;

FIG. 4 is a top view thereof;

FIG. 5 is a perspective view of an alternative embodiment of a table base in accordance with the new design;

FIG. 6 is a front elevational view thereof, a rear elevational view being a mirror image thereof;

FIG. 7 is a right side elevational view thereof, a left side elevational view being a mirror image thereof; and,

FIG. 8 is a top view thereof.

The broken lines in the figures are for illustrative purposes only and form no part of the claimed invention.
